UNITED STATES PATENT OFFICE.

FRANK B. WELLS, OF MASONVILLE, NEW YORK.

DESIGN FOR A GAME-BOARD.

SPECIFICATION forming part of Design No. 29,250, dated August 16, 1898.

Application filed July 13, 1898. Serial No. 685,874. Term of patent 7 years.

To all whom it may concern:

Be it known that I, FRANK B. WELLS, a citizen of the United States, residing at Masonville, in the county of Delaware and State of New York, have invented and produced a new and original Design for a Game-Board, of which the following is a specification, reference being had to the accompanying drawings, forming a part thereof, in which—

10 Figure 1 is a plan view of a game-board embodying the features of my design, and Fig. 2 is a section on the line 2 2 of Fig. 1.

The design consists of a box-like body A, in which a horizontal partition B appears above the bottom of the body and below its upper edge. Angular pockets C and C' are located upon the horizontal partition at diagonally-opposite corners of the box-body, and each pocket is provided with an opening in its diagonal or inner member. In each of the other two corners of the box-body the horizontal partition B is provided with an opening, the openings being designated as D and D', while another opening D² appears in the central portion of the said partition. 25

I claim—

The design for a game-board, herein shown and described.

FRANK B. WELLS.
